DALMAR T. BROWNLEE, OF INDIANAPOLIS, INDIANA

STARTER DEVICE

Application filed August 4, 1930. Serial No. 472,935.

This invention relates generally to means whereby to control a rotary pinion in the operation of starting rotation of a gear wheel by the pinion and the power of an electric 5 starter motor, the invention having reference more particularly to a starter device having the general characteristics of that disclosed in my application for Letters Patent filed October 20, 1927, Serial No. 227,527; the 10 present invention relating especially to improvements in pinion-controlling means of starter mechanism.

An object of the invention is to provide an improved starting mechanism that shall be 15 of simple and not costly construction, which shall be capable of quietly operating and not likely to be damaged by misuse of an ignorant or careless operator.

Another object is to provide an improved 20 starter device that permits considerable variation of the accuracy of the parts in manufacturing without affecting the efficient operation of the device.

A further object is to provide a starter 25 device of such construction as to be capable of uniformly efficient operation under the usual conditions of operation of a motor-vehicle without requiring extraordinary skill on the part of an operator.

A still further object is to provide pinion-controlling mechanism for starter apparatus 30 that shall be of such construction as to be adapted to be operated and controlled without shock and noise when the starting motor 35 goes into action, and which shall not be likely to become locked as result of thoughtlessly or improperly attempting to begin operation of the starting mechanism; which starter device shall be of such construction as to be 40 extremely compact and strong, not likely to need repairing, and shall be adapted to be durable and economical in use.

With the above-mentioned and other 45 objects in view, the invention consists in novel pinion-controlling mechanism adapted for structural association with generally-controlled starter devices, more particularly to start motor-vehicle engines or motors; the invention consisting also further in the parts, 50 and in the combinations and arrangements of

parts, as hereinafter particularly described and further defined in the claims appended hereto.

Referring to the accompanying drawings,—Figure 1 is a longitudinal central section, partially in elevation, showing a construction substantially in accordance with this invention, Fig. 2 is a view similar to Fig. 1 but showing the various parts in different positions; Fig. 3 is another similar view 55 in which various parts appear relatively as seen following a starting operation; Fig. 4 is an end view of a shifting drive housing; Fig. 5 is a longitudinal central section of the housing; Fig. 6 is an external view of driving and controlling devices comprising important co-operating parts of the invention, being on an enlarged scale; Fig. 7 is generally similar to the preceding view but in which one of the parts is in section to more 60 clearly expose an important feature; Fig. 8 is an end view of one of the driving and controlling devices; Fig. 9 is an end view of another of the driving and controlling devices; Fig. 10 is a transverse section through the 65 driving and controlling devices; and Fig. 11 is a perspective view of one of the devices comprised in the driving and controlling apparatus.

Similar reference characters in the various 70 figures of the drawings indicate corresponding elements or features of construction herein referred to in detail.

This invention, although adapted for various mountings, will be described in its relation to a conventional internal combustion engine having a crank case, portions 1 and 1' of which are indicated as being suitable for supporting an electric starter which in the present case comprises an inclosing 85 casing adapted to constitute a supporting frame having a body portion 2 and a head portion 3 provided with a flange 4 for attachment to the crank case in which is an opening 90 receiving the head portion, the body portion 2 supporting a suitable casing extension 5 in which a suitable motor armature 6 is arranged. The armature has a drive shaft 7 having a diametrically smaller extension portion 8 which is provided with a 95 100

journal 9 that is suitably supported in a bearing 10 with which the head of the casing is provided. The shaft portion 8 is straight and smooth as is the drive portion 7 of the shaft which forms a shoulder 11 on its end from which the portion 8 projects. Preferably the drive portion of the shaft has a spacing collar 12 thereon adjacent to the armature.

- 10 An improved controlling housing is provided which comprises a cylindrical shell 13 having a drive head 14 that is fitted to longitudinally slide on the main shaft portion 7 to be rotated thereby by means of suitable splines 15 and 16. The shell has drive lugs 17 projecting inward at a suitable distance from the head 14, and the shell has also a counterbore 18 adjacent to the lugs to receive a controlling nut which will be further described, the shell having a groove 19 that opens into the counterbore to receive a split ring 20 for retaining the nut in the counterbore. The shell of the housing has a circumferential groove 21 to receive a shifter fork.
- 15 A suitable controlling lever 22 is supported by a pivot 23 mounted upon the upper portion of the casing and may be adapted to be connected through a spring to a foot-lever and conventionally has a retracting spring, the lever 22 being provided also with a shifter fork 24 arranged to operate in the groove 21 whereby to longitudinally move the housing along the armature shaft.
- 20 An improved pinion carrier and controller

- 25 is provided which comprises a sleeve 25 that is movably guided on the guide portion 8 of the shaft and has a pinion 26 fixed on one end portion thereof to be moved into driving connection with a toothed ring gear 27 with which the engine fly-wheel commonly is provided and received partially into the casing through an aperture 28 with which the head portion 3 is provided. The inner end of the sleeve is adapted to be stopped 30 against the shoulder 11 and is provided with lugs to be engaged by the lugs 17, the structure preferably comprising a flange 29 fixed to the sleeve and suitably cut away to constitute lugs 30 facing in one and the same direction, the backs of the lugs being beveled to afford clearance while the sleeve is rotated and carries the lugs 30 backward towards the head 14 of the housing. The sleeve has novel control members 31 having each an approximately conical surface adapted to be frictionally clutched to push the sleeve outward. The members are spaced apart and each one has a continuous long-lead or rapid screw-face 32 and also a correspondingly pitched guide face 33, the latter being opposite to the face 32; also each member 31 has a wall face 34 that is located farther than the face 33 from the face 32 in advance of the face 33, to afford clutch clearance space opposite to the screw-face 32. Preferably the surface

of one of the members 31 has a small indentation or oval recess 35 arranged in proximity to the flange 29. An annular nut 36 is fitted in the counterbore 18 and has a diametrically smaller inner end portion 37 that extends into the body portion of the housing 13 and has notches 38 in its end face to receive the lugs 17. The nut has also internal long-lead screw threads 39 to co-operate with the faces 32 and 33 in close fitting arrangement in the grooves formed between opposite faces. The nut has a diametrically reduced portion 40 to clear the retaining ring 20. The body portion of the nut has a radial guideway 41 so located as to lead to the indentation 35 when the lugs 30 are in contact with the nut, and a pin device 42 is arranged in the guideway so as to enter the depression 35 or to have contact with the surface of the adjacent member 31, the device having a guide stem 43 and a compression spring 44 on its back, the spring having a bearing against the wall of the housing 13, to prevent improper shifting of the controlling sleeve that might be due to vibration of the various parts.

The starting motor being at rest and the various elements approximately in positions shown in Fig. 1, upon appropriate movement of the lever 22 by such means as may be provided the housing 13 is moved forward with consequent forward movement of the nut 36. The nut automatically becomes clutched to the inclined or wedge-like surface of the controller members 31 and thereby pushes the sleeve 25 out, and the pinion thereon forward into operative engagement with the fly-wheel of the engine, as indicated in Fig. 2. The motor is to be started through appropriate instrumentality which may be afforded so as to start the engine which in practice will normally become operated and, as the fly-wheel starts to rotate at high speed the pinion is rotated and causes the sleeve to be rapidly screwed back into the nut without opposition of the housing while the driving lugs therein are becoming disengaged. The housing becomes retracted by means of the retracting spring to its initial position, the nut having no clutching action on the sleeve during this operation. The pin device 42 operates automatically to compensate for back lash of the associated parts. Upon initial movement designed to carry the pinion forward the clearance afforded by the set back face 34 permits sufficient longitudinal movement of the nut to insure the required clutching contact to advance the sleeve. When the nut threads are between the screw faces 32 and 33 clutch action cannot occur.

What is claimed as new is:

1. A starter device including a shiftable sleeve provided with a conical clutch surface having a helical thread groove, one portion of the groove having less width than the remain-

ing portion thereof, a threaded nut operable on the clutch surface of the sleeve, the thread in the nut having a width corresponding to the lesser width of the groove, a pinion carried by the sleeve, and means to rotate the sleeve.

2. A starter device including a rotary housing provided therein with a screw thread, a sleeve in the housing to be rotated thereby provided with a conical clutch surface having a helical thread groove differing in width in different portions thereof, the groove operatively receiving the screw thread of the housing and permitting lateral play of the thread in the broader portion of the groove, and a pinion secured to the sleeve.

3. A starter device having a sleeve provided with helical clutch and thread members having each a continuous screw face on its forward edge and a guide face on its opposite rearward edge having different portions thereof situate at different distances from the screw face, the circumferential surface of each thread member being inclined, a controlling housing, a nut supported in and controlled by the housing and having means to co-act with the clutch and thread members alternately to push and to rotate the sleeve, and a pinion secured to the sleeve.

4. A starter device having a wedge-faced sleeve provided with a helical thread groove differing in width in different portions thereof, the sleeve having a drive lug fixed thereon adjacent to the beginning of the broader portion of the groove, a pinion fixed to the sleeve adjacent to the end of the narrower portion of the groove, a driving housing on the sleeve having a lug to engage the lug on the sleeve, and a nut in the housing to engage the wedge-face of the sleeve, the nut having a screw thread operating in the thread groove.

5. A starter device including a sleeve having helical clutch and thread members, the opposite sides of each member having each a screw face, the circumferential surface of each member being inclined and one of the members having an indentation in its surface, a pinion fixed to the sleeve, a controlling housing, and a nut controlled by the housing and having means to co-act with the clutch and thread members alternately to push and to rotate the sleeve, the nut being provided with a spring-impelled detent to slide on the surface of the said member and enter the said indentation.

6. A starter device mechanism including a rotatable housing, a drive shaft guiding and rotating the housing and permitting longitudinal movement of the housing, the shaft having a stop shoulder, means to move and control the housing, a sleeve guided on the shaft to be moved to or from the stop shoulder and having helical controlling members thereon provided each with a conically-inclined friction-clutch surface and

also two approximately perpendicular screw faces on opposite sides thereof, the face at the lower side of the inclined surface having a portion offset into the member, a nut locked in the housing and having screw threads engaging the screw faces on the controlling members of the sleeve but clearing said offset portions, the nut being adapted to have clutching engagement with said inclined surface adjacent to said offset screw face portion, means enabling the housing to rotate the sleeve, and a pinion fixed to the sleeve.

7. A starter device having a housing, a sleeve in the housing, a toothed pinion fixed to the sleeve, a rotary drive shaft guiding the housing and the sleeve and having a shoulder to stop the sleeve, the housing being rotated by the shaft and rotating the sleeve but permitting the sleeve to be rotated in the housing at a higher speed than the housing, means to control longitudinal movement of the housing on the shaft, and co-operating means associated with the sleeve and the housing enabling the housing to clutch and move the sleeve forward along the shaft and also enabling the housing to force the sleeve backward along the shaft with rotary motion at higher speed than the shaft, said means acting to prevent clutching of the sleeve to the housing during the backward movement of the sleeve.

8. A starter device including a rotary drive shaft, a pinion, a hollow housing splined onto the shaft and provided therein with controlling means having co-operating friction clutch apparatus to non-rotatably carry the pinion to an advanced position to start rotation of a fly-wheel, the controlling means being rotated by the housing and provided with co-operating screw faces to rapidly return the pinion from the fly-wheel at higher rotary speed than the housing, and a frictional yielding retarding device co-operating with the controlling means to arrest rotary movement of the clutch apparatus to counteract inadvertent action of the screw faces.

9. In a starter device, the combination with a rotary drive shaft, and an engine gear wheel, of a sleeve on the shaft having a quick-action clutch and screw member, the surface of the member having a depression, a pinion fixed to the sleeve, a housing splined to the shaft, a nut secured to the housing to be rotated thereby and having a rapid-action thread in connection with said member, the nut being adapted to clutch the member to push the sleeve for carrying the pinion to the gear wheel, a pin device carried in the nut and yieldingly projected into said depression, means to control the housing, and means enabling the housing to rotate the sleeve.

10. In a starter device, the combination of a sleeve having a controlling member

thereon, said member having an inclined clutch face and also screw faces on opposite sides of the clutch face, one portion of the lower edge of the clutch face having a clearance space, and a controlling nut on the sleeve adapted to engage the clutch face of said member and having a thread to cooperate with said screw faces, the thread being receivable in said space preceding engagement with the clutch face.

10 In testimony whereof, I affix my signature on the 31st day of July, 1930.
